Primary Examiner — Keli L Hill*Assistant Examiner* — Sara S Sahneh(74) *Attorney, Agent, or Firm* — Stetina Brunda Garred & Brucker(57) **CLAIM**

The ornamental design for an extensible gas valve key, as shown and described.

DESCRIPTION

FIG. 1 is a front perspective view of the extensible gas valve key of the present invention showing the same in an extended configuration;

FIG. 2 is a top view thereof;

FIG. 3 is a front elevational view thereof;

FIG. 4 is a left side view thereof;

FIG. 5 is a right side view thereof;

FIG. 6 is a rear view thereof;

FIG. 7 is a bottom view thereof;

FIG. 8 is a front perspective view depicting the extensible gas valve key of the present invention in a contracted orientation;

FIG. 9 is a top plan view thereof; and,

FIG. 10 is a front elevational view thereof.

The broken lines shown are included for the purpose of illustrating portions of the extensible gas valve key that form no part of the claim.
